UNITED STATES PATENT OFFICE.

KARL A. DOLGE, OF WESTPORT, CONNECTICUT.

SOAP DISPENSER.

Application filed February 19, 1921, Serial No. 446,279. Renewed February 14, 1923.

To all whom it may concern:

Be it known that I, KARL A. DOLGE, a citizen of the United States, residing at Westport, in the county of Fairfield and 5 State of Connecticut, have invented new and useful Improvements in Soap Dispensers, of which the following is a specification.

My present invention pertains to liquid dispensing devices and more particularly to 10 those employed for dispensing liquid soap, and it contemplates the provision in means for the purpose set forth of a container from which liquid may readily and easily be dispensed and this in a simple and highly sanitary manner.

The invention further contemplates the provision in a partially revolving liquid dispenser of means whereby after the dispenser is manually revolved to the limit of 20 its movement only a sufficient amount of liquid will emerge from the dispenser.

The invention further contemplates the provision in a liquid container of such a shape and construction that after dispensing the liquid the container will automatically return to its initial inoperative position.

Other features and characteristics of my invention will be fully understood from the 30 following description and claims when the same are read in connection with the drawings forming part of the specification in which:—

Figure 1 is a side elevation of my novel device as the same appears when attached to a wall or the like.

Figure 2 is a rear elevation of the dispenser and showing the rear construction of the attaching bracket.

Figure 3 illustrates in section the dispenser in its operative dispensing position.

Figure 4 is a transverse section of Figure 1, and;

Figure 5 is a detail view of the inner end 45 of the liquid tube and inserted disk arranged in one end of the tube.

Similar numerals of reference designate corresponding parts in all of the views of the drawings.

50 My novel device comprises the liquid dispenser or container 1, which container is of the peculiar construction illustrated. The bottle 1 is increased in size at its lower end and this increase not only adds to its attractiveness but assures the bottle assuming its proper inoperative position at all times

after use irrespective of whether it contains a large or small quantity of liquid in the same. The bottle in other words might be termed as "bottom heavy." In order to 60 doubly assure return of the bottle to its normal position a circumferential recess is formed in the upper portion thereof and adapted to seat in the recess and retain the bottle 1 in pendent position in a ring 2.

65 This ring 2 completely surrounds the bottle and at its forward end the arms of the ring are separated by a slight intervening space. The arms extend forwardly (Figure 4) and interposed in the space between the 70 forwardly reaching portion of the arms is a finger manipulative element 3.

A pin is employed to clinch the forward portions of the ring together about the neck of the bottle, and at the same time the pin 75 retains the finger piece between the forward portions of the ring.

At its rear, the ring 2 is formed integral with a shank 4, and surrounding the shank 4 is a collar 5 that terminates in a bracket 6, 80 in which are fastening apertures by which the device may be secured to a wall.

As clearly shown in Figure 2 the shank 4 is provided with a stud or projection 7 and the rear of the bracket slot 8 in which the 85 stud 7 travels during movement of the bottle 1.

Surrounding the extreme upper end of the bottle 1 is a band 9 and screwed or otherwise retained in the mouth of the bottle 1 90 is a tube 10 and surrounding the tube and adapted to rest against the upper end of the bottle neck is a washer or gasket 11 which prevents seepage of liquid from the bottle when said bottle is in its operative position. 95

The tube 10 is provided with an interior bore 13 and at its lower end the tube is decreased in circumference as indicated by 12.

By reference to Figures 3 and 5 it will be manifest that in the extreme inner end of the tube 10 there is a countersink a disk 15 that is provided with the orifice 16 that registers with the interior bore of the tube 10. This disk 15 is retained in the end of the tube by tamping the outer ends of the tube over the disk 100 as shown. In its upper end the tube is provided with the outlet orifice 16 that registers with the bore 13 and movable in the bore 13 is a check ball 14.

In the practical use of the device, the dispenser is secured to a wall by passing attaching means through apertures in the bracket 110

portion 6. The tube 10 is then removed from the bottle 1 and liquid soap is placed in the bottle. The weight of the bottle will maintain the same in the position shown in 5 Figures 1 and 2 with the pin 7 of shank 4 at the lower end of the slot 8.

When it is desired to dispense soap, one hand of the operator is properly positioned to receive said soap, and with the other hand, 10 the operator grips the finger element 3 between the index, middle finger and thumb, and whirls or revolves the ring 2 within the collar 5. This manifestly revolves the bottle 1. During this revolving motion liquid 15 passes through the bore 13 of tube 10 upon the hand of the user and the ball 14 will rush from the bottom of the tube to the orifice 16 and prevent further dispensing of liquid. Naturally liquid will pass the ball 20 during the passage of the ball from one to the other end of the tube, but when the ball arrives at the orifice 16 no liquid can pass from the interior bore of the tube, and hence 25 no waste of soap is occasioned during operation of the dispenser, as only a sufficient quantity of soap will leave the dispenser and the possibility of splashing soap on the operator's clothing is precluded. Immediately upon release of the finger piece 3, the 30 bottle will assume its normal position due to its weighted lower end.

When the bottle is in the position shown in Figure 3, it will be precluded from making a complete revolution because the pin 7 35 will be stopped in its upward movement by contact with the upper end of the arcuate slot 8.

It will be appreciated that this pin prevents swinging of the bottle after its release. 40 The device is simple to operate, easy to install and inexpensive to produce and comprises no delicate parts such as are liable to get out of order after a short period of use. Moreover, the arrangement of finger piece 45 with respect to the bottle assures sanitation as the hands of the user do not contact with the outlet of the tube 10 and said thumb piece prevents operation of the bottle on a small surface and at the same time leaves 50 the bottle clean.

The ball 14 moreover, permits only a specific amount of soap to leave the container at a time and also prevents evaporation of the soap or entry of dust and dirt into the 55 inside of the bottle during cleaning of the room in which the dispenser is placed.

The dispenser is so constructed and finished that it will greatly enhance the finished appearance of a bath or other room 60 irrespective of the quality of the other fixtures contained in the room.

I would distinctly have it understood that I do not wish to confine myself to any particular material, size or shape in making the 65 device, as in the future practice of the invention such changes or modifications may be made as fairly fall within the scope of the appended claims.

Having described my invention, what I claim and desire to secure by Letters Patent 70 is:—

1. In a liquid dispensing device, the combination of a liquid container of increased size at its lower end, a circumferential recess formed in the upper outer surface of 75 the container, a band that seats in the recess and having forwardly reaching portions that are separated from each other by a slight intervening space, a finger portion confined in the space and secured to the forwardly reaching portions of the band, a shank formed integral in the rear of the band, a collar surrounding a portion of the shank, a base formed on the collar, an arcuate slot formed in the base, and a projection 80 formed on the end of the shank for limiting movement of the shank with respect to the collar. 85

2. In a liquid dispensing device, the combination of a liquid container of increased size at its lower end, a recess formed in the container, a ring that seats in the recess, a tube that seats in the mouth of the container, an internal bore formed in the longitudinal center of the tube, a check ball that moves in the tube, an outlet orifice formed in the tube and registering with the internal bore of the tube, a disk formed in the inner end of the tube and having an orifice that registers with the bore of the tube, a finger piece secured to the forward end of the ring, a shank formed integral with the ring at the rear thereof, and a casing that surrounds a portion of the shank; said casing having a base, an arcuate slot formed in the base and a projection that moves in the slot and provided on the inner end of the shank; the shank being revoluble in the casing and its movement being limited by the contacting 100 of projection with the ends of the slot. 105

3. In means for the purpose set forth the combination of a liquid container being so constructed and arranged that it will of itself assume a perpendicular position, a dispensing outlet formed in the container, a ring surrounding the container, a finger portion secured to the ring, a shank formed integral with the ring, casing surrounding the shank; the shank being revoluble with respect to the casing, an arcuate slot formed 115 in rear of the casing, and a projection formed on the shank and confined in the slot for limiting the revoluble movement of the shank in the casing. 120

4. In a liquid dispensing device, the combination of a casing, a base formed integral on the casing, a slot formed in the base, a shank revoluble in the casing and a projection formed on the shank and confined in the slot, a band, formed integral with the 125 130

shank, a finger piece formed and arranged in the band, a container secured in the band and being bottom heavy; whereby when the shank revolves to its limit with respect to the casing, the bottle will immediately assume of itself a perpendicular position.

5. In a liquid dispensing device, a bottle having a lower end of increased size, a tube arranged in the mouth of the bottle, a bore 10 extending longitudinally in the tube, a check ball that moves in the bore, a disk for retaining the ball in the lower end of the tube, an orifice of decreased size formed in the upper end of the tube in registration 15 with the bore thereof, a band secured to the

bottle, a portion secured to the band, a shank formed with respect to the band, a casing surrounding the shank, a projection formed on the shank and an arcuate slot formed in the base of the casing, to receive 20 the projection and to limit movement of said projection.

In testimony whereof I have hereunto set my hand in presence of two subscribing witnesses.

KARL A. DOLGE.
